(57) CLAIM

The ornamental design for an anterior cervical plate, as shown and described.

DESCRIPTION

FIG. 1 is a top plan view of the anterior cervical plate of my

new design;

FIG. 2 is a bottom plan view thereof;

FIG. 3 is a left side elevational view thereof, the right side elevational view being a mirror image thereof;

FIG. 4 is a first end view thereof, the second end view being a mirror image thereof;

FIG. 5 is a top plan view of a second embodiment of the design of FIG. 1;

FIG. 6 is a bottom plan view thereof;

FIG. 7 is a left side elevational view thereof, the right side elevational view being a mirror image thereof;

FIG. 8 is a first end view thereof, the second end view being a mirror image thereof;

FIG. 9 is a top plan view of a third embodiment of the design of FIG. 1;

FIG. 10 is a bottom plan view thereof;

FIG. 11 is a left side elevational view thereof, the right side elevational view being a mirror image thereof;

FIG. 12 is a first end view thereof, the second end view being a mirror image thereof;

FIG. 13 is a top plan view of a fourth embodiment of the design of FIG. 1;

FIG. 14 is a bottom plan view thereof;

FIG. 15 is a left side elevational view thereof, the right side elevational view being a mirror image thereof;

FIG. 16 is a first end view thereof, the second end view being a mirror image thereof;

FIG. 17 is a top plan view of a fifth embodiment of the design of FIG. 1;

FIG. 18 is a bottom plan view thereof;

FIG. 19 is a left side elevational view thereof, the right side elevational view being a mirror image thereof;

FIG. 20 is a first end view thereof, the second end view being a mirror image thereof;

FIG. 21 is a top plan view of a sixth embodiment of the design of FIG. 1;

FIG. 22 is a bottom plan view thereof;

FIG. 23 is a left side elevational view thereof, the right side elevational view being a mirror image thereof; and,

FIG. 24 is a first end view thereof, the second end view being a mirror image thereof.
